Primary Examiner — Mimosa De(74) *Attorney, Agent, or Firm* — Rumit Ranjit Kanakia(57) **CLAIM**

The ornamental design for a folding chair, as shown and described.

DESCRIPTION

FIG. 1 is a front view of a folding chair showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view of a folding chair showing my new design;

FIG. 8 is a perspective view of a folding chair showing the headrest on the folding chair is open; and,

FIG. 9 is a partial enlarged view of FIG. 8.

The broken lines in the figures are for the purposes of illustrating portions of the folding chair, which form no part of the claimed design.
